UNITED STATES PATENT OFFICE.

EDWARD JOHN RENKENBERGER, OF BUFFALO, NEW YORK.

REINFORCED WIRE FERRULE FOR WOODEN HANDLES.

1,250,508.

Specification of Letters Patent. Patented Dec. 18, 1917.

Application filed July 25, 1913. Serial No. 781,153.

To all whom it may concern:

Be it known that I, EDWARD J. RENKENBERGER, a citizen of the United States, residing at Buffalo, in the county of Erie and State of New York, have invented certain new and useful Improvements in Reinforced Wire Ferrules for Wooden Handles; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to tool handles, and has for its object to provide a reinforcing wire ferrule for the handle which will afford protection and impart increased strength to the face-end of the tool receiving portion of the handle and at the same time permit the ferrule to the rear of the face-end to expand and contract to conform to irregularities in the handle with the view of maintaining the tension-grip of the wire coils on the handle and prevent or restrain the tendency to split the handle by forcing the tool into place. Also to provide what for convenience may be termed a buttress at the face-end of the handle so that when it is hard to remove the handle from the tool blows may be imparted to the face-end of the handle without injury to the handle or ferrule.

To the accomplishment of the foregoing and such other objects as may hereinafter appear the invention consists in the features hereinafter particularly described and then sought to be clearly defined by the claims, reference being had to the accompanying drawing forming a part hereof and in which:

Figure 1 is a longitudinal section through a handle and ferrule, illustrating one form of the invention;

Fig. 2 a similar section showing a modification;

Fig. 3 a similar section showing another form;

Fig. 4 a cross section on the line 4—4 of Fig. 1;

Fig. 5 a cross section on the line 5—5 of Fig. 1.

In the drawing the numeral 1 designates a wooden handle which may be of any approved configuration and as illustrated is formed with a swell 2 near the front end

and with a central bore 3 to receive the tang of the tool to which the handle may be attached. The handle is formed at its tool receiving end with a reduced central portion 4 and a shoulder 5 at the base of the reduced portion, and with a shoulder 6 adjacent or next to the grip portion of the handle.

The ferrule 7 is formed of wire of any preferred form in cross section but preferably round and has one end secured to the tool receiving end of the handle and the other end to the handle at or adjacent to the grip portion of the handle, the intermediate portion of the wire strand being wound tightly under considerable tension around the handle but the convolutions left unattached from each other and from the handle except where they encircle the reduced portion in front of the shoulder at the tool receiving end and at the point where the end next to the grip portion is secured to the handle. This enables the wire ferrule to expand and contract under the variations in the diameter of the handle due either to expansion caused by driving the tool tang in place or contraction by reason of shrinkage of the wood. Under either condition the ferrule maintains its tension on the handle, and if there be expansion at one point there will be a corresponding drawing on the other coils and thus not only will the tendency to split due to driving in a tool tang be restricted but also an adjustment of the coils to the changing conditions be provided for.

In order to most securely hold the end of the wire ferrule to the tang receiving end of the handle and also to afford a strong protection to that end and likewise provide a stable buttress to receive the blows for disengaging the handle and tool tang when there is an exceptionally tight fit between the two parts, the end of the wire is provided with a prong 8 to enter the reduced end portion of the handle and then the wire is wound tightly around the reduced portion 4 in layers or to form a series of adjacent superimposed convolutions 9 between the shoulder 5 and the end of the reduced portion 4 as illustrated in Figs. 1, 2 and 3, and then continued in a convolute manner around the handle to the point where the other end of the wire is secured to the handle at or adjacent to the grip portion by a prong 10 embedded in the handle and at such point secured to the adjoining convolution by a

drop of solder 11. The first convolution from the prong 8 may proceed directly around the reduced portion 4 as illustrated in Fig. 1 but it is preferred to provide a straight portion or bend 12 extending parallel with the surface of the reduced portion 4, and preferably embedded so as to lie flush with the surface, as indicated in Fig. 2 of the drawing, the straight portion extending from the prong to the shoulder 5; or the prong may be next to the shoulder and the straight portion 13 extend toward the end of the reduced portion as indicated in Fig. 3. In either case the superimposed and adjacent coils extend across the straight portion of the wire and tend to hold it in place, and as one or more of the superimposed coils will bear against the shoulder 4 end thrust against the end of the handle is resisted and the coils prevented from being forcibly dislodged or moved from position.

To protect the superimposed adjacent coils around the reduced end 4 of the handle, a band or cap of solder 14 is applied across the outermost superimposed coils and also over the topmost coils of the series of adjacent coils, thus securely fastening the coils together at such points of contact as well as protecting the coils and together with the coils forming a stable buttress to receive the blows of a hammer for detaching the handle and tool in the event of the two having an exceptionally tight fit to each other.

Having described my invention and set forth its merits what I claim is:

- 35 1. A handle and reinforcing wire ferrule encircling the handle, one end of the wire being attached to the tool end of the handle and the other end to the handle toward its grip portion, the ferrule being formed of coils with those at the tool receiving end arranged to constitute a series of adjacent superimposed concentric convolutions, substantially as described.
- 40 2. A handle and reinforcing wire ferrule encircling the handle, one end of the wire being attached to the tool end of the handle and the other end to the handle toward its grip portion, the ferrule being formed of coils with those at the tool receiving end arranged to constitute superimposed concentric convolutions, substantially as described.
- 45 3. A handle and reinforcing wire ferrule consisting of the handle having at its tool receiving end a reduced portion and a shoulder at the base of the reduced portion, and a wire ferrule encircling the handle, the opposite ends of the wire being attached to the

handle, and the wire at the tool receiving end being wound around the reduced portion of the handle to form a series of adjacent superimposed convolutions between the shoulder at the base of the reduced portion and the outer end of the latter, substantially as described.

4. A handle and reinforcing wire ferrule consisting of the handle having at its tool receiving end a reduced portion and a shoulder at the base of the reduced portion, and a wire ferrule encircling the handle, the opposite ends of the wire being attached to the handle, and the wire at the tool receiving end having a part bent to lie parallel with the surface of the reduced portion and also wound around said portion transversely across the bent portion of the wire to form a series of adjacent superimposed convolutions overlying the bent portion between the shoulder at the base of the reduced portion and the outer end of the latter, substantially as described.

5. A handle and reinforcing wire ferrule consisting of the handle having at its tool receiving end a reduced portion and a shoulder at the base of the reduced portion, a wire ferrule encircling the handle and having its opposite ends attached thereto, the wire at the tool receiving end being wound around the reduced portion to form a series of adjacent superimposed convolutions between the shoulder at the base of the reduced portion and the outer end of the latter, and a metallic cap applied across the outermost superimposed end coils and over the topmost coils of the series of adjacent coils, substantially as described.

6. A handle and reinforcing wire ferrule consisting of the handle having at its tool receiving end a reduced portion and a shoulder at the base of the reduced portion, a wire ferrule encircling the handle and having its opposite ends attached thereto, the wire at the tool receiving end being wound around the reduced portion to form superimposed convolutions between the shoulder at the base of the reduced portion and the outer end of the latter, and a metallic cap applied across the outermost superimposed end coils and over the topmost coils, substantially as described.

In testimony whereof I affix my signature in presence of two witnesses.

EDWARD JOHN RENKENBERGER.

Witnesses:

GEORGE CHARLES RENKENBERGER,
JOHN E. WOLF.

It is hereby certified that Letters Patent No. 1,250,508, granted December 18, 1917, upon the application of Edward John Renkenberger, of Buffalo, New York, for an improvement in "Reinforced Wire Ferrules for Wooden Handles," were erroneously issued to the inventor, said Renkenberger, whereas said Letters Patent should have been issued to *George C. Renkenberger*, said George C. Renkenberger being owner *by mesne assignments* of the entire interest in said invention, as shown by the records of assignments in this office; and that the said Letters Patent should be read with this correction therein that the same may conform to the record of the case in the Patent Office.

Signed and sealed this 12th day of February, A. D., 1918.

[SEAL.]

J. T. NEWTON,

Commissioner of Patents.
